DESIGN FOR A FIXED FOCUS ENLARGER

Herman Neuwirth, New York, N. Y., assignor to
Testrite Instrument Company, Inc., New York,
N. Y., a corporation of New York

Application February 7, 1949, Serial No. 728

Term of patent 14 years

(Cl. D61—1)

To all whom it may concern:

Be it known that I, Herman Neuwirth, a citizen of the United States, residing in New York city, in the county of Kings and State of New York, have invented a new, original, and ornamental Design for a Fixed Focus Enlarger, of which the following is a specification, reference being had to the accompanying drawing, forming a part thereof.

In the drawing:

Figure 1 is a perspective view of the fixed focus enlarger, viewed from front of device, showing my new design.

Figure 2 is a rear elevation.

Figure 3 is a side elevation.

Figure 4 is a front elevational view.

I claim:

The ornamental design for a fixed focus enlarger, as shown.

HERMAN NEUWIRTH.
